Primary Examiner — T Chase Nelson*Assistant Examiner* — Sydney Margaret Parsley(74) *Attorney, Agent, or Firm* — Neugeboren O'Dowd PC(57) **CLAIM**

The ornamental design for a perforated panel for frame end, as shown and described.

DESCRIPTION

FIG. 1 is a front perspective view of a perforated panel for frame end;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear perspective view thereof.

The shade lines in the Figures show contour and not surface ornamentation.

The broken lines show portions of the perforated panel for frame end that form no part of the claimed design.
